UNITED STATES PATENT OFFICE.

ARTHUR NORRISON MARR, OF THORNER, NEAR LEEDS, ENGLAND.

MACHINE FOR DRYING YARN AND TEXTILE GOODS.

No. 881,602.

Specification of Letters Patent.

Patented March 10, 1908.

Application filed July 20, 1906. Serial No. 327,040.

To all whom it may concern:

Be it known that I, ARTHUR NORRISON MARR, a subject of the King of Great Britain and Ireland, residing at "Rangiora," Thorner, near Leeds, in the county of York and Kingdom of England, have invented new and useful Improvements in Machines for Drying Yarn and other Textile Goods or Materials.

This invention has reference to machinery employed for drying yarns in hanks, or other materials used in textile goods, or for the goods themselves, such as, hosiery and the like, all of which are hereafter termed and included in the term "materials."

Hitherto in machinery employed for this purpose when provision has been made for circulating air through the material operated upon, the said air has only been used for drying purposes, and it has frequently been made to travel in an upward direction or both upwards and downwards in the drying chamber. This has the effect in some cases, where the current of air is too strong, particularly say, in the case of yarns, of causing the hanks to tangle, and in other cases causes the fibers to lie in the wrong direction. Further, no provision has been made for exhausting the air from the drying chamber, although in some cases attempts have been made to force or squeeze the moist air out of the drying chamber through openings at or near its top by means of the pressure of the incoming heated air. Also, when the material has been mounted upon pins, the latter have been fixed to traveling chains to which an intermittent traversing motion has been imparted. In these machines no provision has been made for causing the pin or pole carrying the material to be intermittently revolved. Consequently, there has been a danger of the water or other moisture in the material being allowed to collect or remain locally and unevenly in the material during the drying operation, thereby deteriorating, when not actually injuring, such portion or portions of the material.

Various attempts have been made,—with more or less success,—to remedy the above defects, and the object of this invention is to provide a machine in which the air for drying and also for conditioning the material afterwards is made to pass freely and as evenly as possible through the material being

dried with less risk in the case of yarn of entangling it and also securing better quality of drying at less cost. The material in this machine is arranged to hang vertically and all of the air currents are made to pass or travel in a vertical and downward direction, the object being to open as well as to straighten the material during the drying process. Definite provision is also made for intermittently revolving the poles which support the material during the drying and conditioning process so that the moisture shall not have time to collect at any one point.

The requisite number of hanks or pieces of material to fill a pole in this machine can be placed thereon while the machine is in motion and without stopping the traverse of the poles through the drying chamber.

In the hereinafter described machine the poles are arranged to be traversed longitudinally through the drying chamber, their ends being supported by races fixed to the sides of the drying chamber, and the poles are caused to be either continuously or intermittently moved through the same by projections fixed upon endless chains. Provision is also made for raising the poles by projections fixed to vertical lifting chains for conveying them successively to one or more races on a higher level and for finally returning them to the inlet end of the machine in proper order for being again traversed through the drying chamber. An additional fan is also provided for the definite purpose of exhausting the moisture in the drying chamber of the machine, and also for causing a slight movement of air into the machine from the room at the point where the operatives attending the machine stand.

By the above means the whole of the air in the machine is made to circulate alternately through the material and the heating surface and it enables a greater amount of duty being obtained from a given amount of heating surface.

I attain these objects by the mechanism illustrated in the accompanying drawings, in which:

Figure 1 is a longitudinal section through the drying chamber. Fig. 2 a plan of same showing the sparred floor of the drying chamber, and one chamber showing the

- 22
- fans and the driving gear, and the other fan chamber showing the heating radiators and the exhaust fan. Fig. 3 an end elevation of the closed end of the machine with 5 boarding removed to show the circulating fans, cone driving gear, and the heating radiators. Fig. 4 an end elevation of the open end of the machine fitted with the conditioner with portions of the outer casing 10 removed to show one of the fans, and also the positions of the circulating fans and steam radiators in the fan chamber. Fig. 5 a longitudinal sectional elevation taken through the drying chamber and conditioner, 15 and partly through the fan chamber which contains the cone driving gear. Fig. 6 a part sectional elevation showing the lifting gear at the closed end of the machine provided with two races upon which two tiers of poles travel. 20 Fig. 7 a front elevation of the same. Fig. 8 a part longitudinal section of machine provided with four races upon which four tiers of poles travel for causing the material to travel four times through the drying chamber. 25 Fig. 9, an enlarged part elevation of means for intermittently rotating the poles. Fig. 10, a plan of the same. Fig. 11, a small diagrammatic view showing the arrangement of racks. 30 The machine consists of an oblong drying chamber *a* having one of its ends *b* open, and the other end *c* closed, constructed with framing of timber, iron, or steel, in convenient sections lined and covered in with 35 boarding or other suitable material. The drying chamber is provided with a latticed or perforated floor 33 and ceiling 34. On either or on both sides of the drying chamber *a* is a narrower chamber *d*, *e*, but of 40 equal length and height and of similar construction. In each narrower chamber is or are one or more fans *f* mounted on the same axis or shaft *g* constructed so as to move air parallel thereto, and so placed that 45 they both draw their supply of air from the drying chamber *a* through openings or ports *h* at the bottom of the partition *i* between the two chambers as indicated by arrows in Fig. 3 and then propel the air back into 50 the drying chamber *a* through similar openings or ports *j* at the top of the same partition, thus maintaining a continual circulation of air downwards through the material which is suspended from poles *k* in 55 the drying chamber. Heating surface in the form of steam tube radiators *l* or coils is fixed in each fan chamber, so that the air so circulated by the fans is heated, and kept as hot as may be desired. 60 In order to facilitate the escape of moisture from the drying chamber *a* sliding doors *m* are provided in the outer partition of each fan chamber at and near the opening required opposite the pulley *n* for the passing

of the belt used for driving the circulating 65 fans, and on the suction side of them. By these doors the quantity of air so drawn in by the fans may be regulated, thus also regulating to the same extent the rate at which the air in the machine shall be changed and 70 renewed.

To give further control over the changing of the air in the drying chamber *a*, an additional fan or fans *o*, Figs. 2 and 3, may be fixed in any fan chamber, and separately 75 driven at any desired speed, so as to draw its supply of air from the bottom of the drying chamber. Two tiers of poles *k* or any multiple of two, say, four, in pairs, each pair consisting of an upper tier and a lower 80 tier, and superposed, travel simultaneously through the drying chamber, the lower inwards, and the upper outwards, as indicated by the arrows in Fig. 1, along an upper race *p* and a lower race *q*, these races consisting respectively of one and of two bars of angle iron secured to each side of the drying chamber. At the open end *b* of the machine the lower bars of the lowermost race *q* project from the framing and on these bars the 85 poles *k* from which the material to be dried is freely suspended are placed by the attendant, one by one, so that they are taken forwards in succession by the endless traveling chains *r*, one at each side of the drying 90 chamber, on which at short regular intervals are provided projections *s*, Figs. 6 and 7, which propel the poles *k*, at proper distances apart, between the double bars forming such lower race or races *q*, and upon the single 95 bars forming the upper race or races *p*.

The poles *k* when required may be caused, as they travel horizontally, to receive an intermittent or a continuous rotary motion by means of any suitable arrangement such as 10 rings or ferrules *k*¹ fixed to the ends of the poles *k*, as shown at Figs. 9 and 10. In the periphery of each ring *k*¹ is formed a number of elongated holes or recesses *k*² at equal distances apart. The holes *k*² are made to 11 mesh with a number of rack teeth *k*³ cast, or otherwise formed, or fixed, to the race *r*, or to a projection fixed to the sides of the drying chamber. The teeth *k*³ are arranged in groups at irregular or regular intervals apart, as shown in the diagrammatic view Fig. 11 so as to give the desired intermittent rotary movement to the poles *k* and consequently a more even and complete exposure of the material to the downward current of 12 heated air.

When any pole *k* arrives at the inner and further end of the first or of any intermediate lower race *q*, it descends on a curved continuation thereof *t*, Fig. 6, until it is free 13 from the path of the projections *s* on the traveling chains *r* and enters the path of the two projections horizontally opposite each

other u provided on the lifting chains v , Figs. 6 and 7. These lifting chains at the closed end of the machine have a vertical orbit or path being actuated by the larger sprocket 5 wheels w which are keyed on the same shaft x as, and close to and inside of similar but smaller wheels y which revolve freely on the same shaft and carry the traveling chains r . One of such shafts x actuating a pair of lifting chains has also fixed upon it the worm wheel z , Figs. 3 and 5, driven by the worm 10 keyed on the same shaft 2 as the cone 3 which is driven by another cone 4 at a relative speed corresponding to the position of the belt 5 connecting the two. The driving cone receives its motion through the pulley 6 on its shaft 7 from any convenient source. The position on the tapered cones of the belt 5 which can be adjusted by any suitable 15 belt motion, thus gives complete control over the speed of the whole of the chains and over the rate at which the material travels through the machine.

When four tiers of poles k are employed, 20 the shaft x has also keyed upon it such sprocket wheels as may be required for driving at the same speed as itself, pitch driving chains 8 or otherwise, the shaft 9 carrying the sprocket wheels which actuate lifting 25 chain 32 provided at the same end c of the machine for raising the poles k from a lower to a higher tier.

Fig. 8 shows the arrangement of four tiers, 30 the material traveling while being dried four times the length of the driving chamber a . In this case the lifting chains 11 at the open end b of the machine are carried and actuated by sprocket wheels 9^a keyed on the 35 shafts 10, one on each side of the drying chamber, on each of which shafts on the fan chamber side of the partitions are also keyed two spur pinions 12 driven by two spur 40 wheels 13 on the shaft 14 which is driven through gearing from the cones 3, 4, as hereinafter explained. The traveling chains r are actuated directly by the sprocket wheels 45 15 at the open end b of the machine, and these are driven from the shaft x through bevel gear 16, Figs. 2 and 3, a longitudinal 50 shaft 17 carried on bearings 18 on the outside of the fan chamber, and worm wheel 19 which is keyed on the shaft 14 on which are also fixed the said sprocket wheels 15.

All the gearing used for connecting the 55 traveling chains r with the lifting chains v and 11 is so proportioned that the passage upwards of any pole k by the lifting chains is done in the same period of time which the traveling chains require to travel the pitch 60 distance between any two successive poles propelled by them.

On the upper bearings 20 of each shaft 22 at the closed end c of the machine carrying the lifting chains v are short ascending races

21, Figs. 6 and 8, for guiding each pole k 65 after being lifted by the chains v into its proper place in the tier p of poles next above.

In order that all chains may be kept taut as they lengthen by use or wear, one of the 70 shafts over which each pair passes is made adjustable as to position, viz. the upper shaft of each pair at the inner or closed end and the lower shaft of each pair at the open end serve the lifting chains in this respect, and the traveling chains r are so adjusted at 75 23, 24, 25, of the open end of the machine by making adjustable the shaft which is the more suitable for that purpose. When the poles arrive at the outer end of the upper race, they are received from the chains on 80 inclined bars 26 fixed so that the poles descend by gravitation to any convenient position.

In order to include in the same process 85 the conditioning of yarn or other material after being dried as preferred by some, instead of placing the dried materials in a conditioning house, I provide an addition 27, Fig. 5, to the drying machine which may be described as follows. The upper 90 part of the machine is prolonged at its open end b , the uppermost tier p of poles k being made considerably longer than the lower tier q , and above it is or are mounted a fan or fans 28 in a close chamber 29 supplied 95 through a duct or passage 30 with fresh air which may have been cooled, moistened, or otherwise treated so as to produce by its contact with the material the effect desired. This air current from the fans 28 is guided 100 into contact with the material as that travels suspended on the poles k from the drying chamber a as far as may be required to the fixed inclined bars 26 before mentioned down which the poles slide to a convenient 105 place.

The action of the machine is as follows:— The moving parts of the machine having been set in motion, the attendant hangs on and spreads out the required number of 110 pieces of material upon each pole, which is then placed upon race q at the feed end of the machine and is carried forward along the race by the projections on the horizontal endless chains in the direction of arrow shown 115 at Fig. 1. The material is thus carried slowly through the drying chamber to its closed end and in so passing through the chamber the currents of air that are circulating from the fan chamber vertically 120 downwards through it are made to pass over and amongst the material operated upon. When the poles carrying the material have reached the closed end of the drying chamber they pass into the curved portion t of the race q and are then caught by the projections on the vertical lifting chains v by which they are raised to the upper race 125.

p, and in entering the latter race they are made to pass over the short race 21. The poles are then carried again through the machine in an opposite direction,—that is in the 5 direction of the arrow from the closed to the open end of the machine,—along the race *p* where they may pass out of the machine either directly down incline 26, or before passing down the said incline have been 10 carried through the conditioning chamber 29. As the material is passed a second time through the machine it will be again subjected to the action of the circulating air. The material during its passage to and from 15 each end of the machine may be acted upon by a rack or racks arranged along the said races, so that it may be turned at intervals to prevent the water or moisture settling at one point of the material. When a number 20 of races are used, as shown at Fig. 8, the material after passing through the machine in one direction is elevated to an upper race first at the closed end of the machine and then after passing a second time through the 25 machine is elevated at the open end thereof for causing it to pass a third time through the drying chamber before it is again elevated at the closed end of the machine to the uppermost race. By these means the material 30 may be carried four or more times through the machine before it passes to the conditioning chamber and out of the machine.

I claim:

35 1. In a drying machine, a drying chamber, a plurality of parallel raceways arranged therein and disposed in different planes, each of said raceways comprising fixed guide rails, a series of supports for carrying the material 40 to be dried, traveling chains provided with projections for engaging said supports and causing them to traverse said raceways, and lifting chains for transferring said supports from one raceway to the next, said lifting 45 chains being driven at such speed that they effect the transfer of a support in the time required by the traveling chains to move a distance equal to the space between two adjacent projections.

50 2. In a drying machine, the combination of a drying chamber open at one end and closed at the other, and provided with a perforated floor and ceiling, with fan chambers arranged of each side of the drying chamber 55 and communicating therewith by ports arranged respectively above and below the perforated ceiling and floor, said fan chambers having fans and heating radiators arranged therein, substantially as described.

60 3. In a drying machine, the combination of a drying chamber open at one end and closed at the other end, and provided with a perforated ceiling and floor, fan chambers arranged on each side of the drying chamber,

ports arranged in the partitions of the drying chamber respectively above and below the perforated ceiling and floor for forming a communication between the said chambers, air circulating fans and heating radiators arranged in each fan chamber, with longitudinal races of angle iron fixed to each side of the drying chamber, each race being arranged in a tier, a pair of sprocket wheels mounted upon a shaft at each end of a tier of races, an endless chain provided with projections and mounted upon the said sprocket wheels at each side of the drying chamber, and poles sliding upon said races, as set forth.

4. In a drying machine, the combination 80 of a drying chamber having a fan chamber on each side thereof and in communication therewith, air circulating fans mounted upon a shaft arranged in each fan chamber at a distance from each end, openings closed by 85 sliding doors in each fan chamber, an exhaust fan mounted in the end of one of the fan chambers, a number of races fixed longitudinally to the sides of the drying chamber, each race being formed of two angle irons arranged in tiers, poles sliding upon said races, a shaft at the end of each race having a pair of sprocket wheels mounted upon it, an endless chain arranged to work over each 90 pair of sprocket wheels to the longitudinal 95 partitions of the drying chamber, projections on the endless chains for traversing the poles along said races, means for actuating said endless chains, and for separately actuating the air circulating and exhaust fans, as 100 set forth.

5. In a drying machine, the combination 105 of a framework open at one end and closed at the other end, divided into three compartments to form a drying chamber with a fan chamber on each side thereof, a perforated ceiling and floor to the drying chamber with a space respectively above the said ceiling and below the said floor, ports in the longitudinal partitions of the drying chamber 110 for forming a communication between the said spaces and the fan chambers, openings in the outer sides of each fan chamber closed by sliding doors, an opening in the closed end of the fan chamber for exhaust 115 purposes, and a conditioning chamber arranged at and projecting from the open end of the machine and provided with an air duct, as set forth.

6. In a drying machine, the combination 120 of a framework open at one end and closed at the other end, divided into three compartments to form a drying chamber with a fan chamber on each side thereof, a perforated ceiling and floor to the drying chamber 125 with a space respectively above the said ceiling and below the said floor, ports in the longitudinal partitions of the drying cham-

ber for forming a communication between the said spaces and the fan chambers, openings in the outer sides of each fan chamber closed by sliding doors, an opening in the 5 closed end of the fan chamber for exhaust purposes, a conditioning chamber arranged at and projecting from the open end of the machine and provided with an air duct, said conditioning chamber being open at the 10 bottom and closed at the top and at the outer end, a fan compartment arranged at the rear end of the last named chamber in communication with the said duct, and a fan mounted upon a separately actuated shaft 15 for drawing air into and forcing it through the conditioning chamber as set forth.

7. In a drying machine, the combination with the drying chamber having an open and closed end, and having a perforated ceiling 20 and floor and with traversing poles upon which the material to be dried is hung, of a number of races fixed at distances apart to each of its longitudinal sides to form horizontal guides for the traversing poles, each 25 race consisting of lengths of angle irons of different lengths arranged at varying distances apart, each horizontal guide being connected together at one end by a vertical guide also provided with a curved lower end 30 and an inclined upper end, a shaft or shafts arranged at each end of horizontal guides having sprocket wheels mounted thereon, an endless chain having projections thereon adapted to work horizontally over the said 35 sprocket wheels at each side of the drying chamber, a second set of sprocket wheels mounted upon the said shafts, an endless chain provided with projections adapted to work vertically over the second set of 40 sprocket wheels and means for intermittently rotating the poles during the passage through the drying chamber, and for actuating the said shafts whereby the poles after 45 passing horizontally through the drying chamber are raised to a race on a higher level for returning them through the machine but in an opposite direction.

8. In a drying machine, the combination with a drying chamber open at one end and closed at the other end and having a perforated ceiling and floor with a space respectively above and below them, of a fan chamber on one side of the drying chamber in communication with said spaces, air circulating fans and heating radiators arranged in the fan chamber, an exhaust fan at the closed end of the fan chamber, means for separately actuating the air circulating and exhaust fans, a pair of races fixed over each 50 other to the longitudinal sides of the drying chamber at a suitable distance apart, each race consisting of a number of strips of angle iron of varying lengths to form two horizontal guides, a shaft or shafts arranged at 55

the end of each of said guides, sprocket 65 wheels mounted upon the said shaft, an endless horizontal chain provided with projections and mounted so as to work over the sprocket wheels near to each longitudinal partition of the drying chamber, poles upon 70 which the material to be dried are placed, said poles being placed across the drying chamber with their ends in the said horizontal guides, means for actuating the said shafts, sprocket wheels, and endless chains 75 whereby the poles are carried horizontally through the drying chamber in one direction, then raised to a higher level of the same race, and returned in an opposite direction through the said chamber to a conditioning 80 chamber at the open end of the machine, said condition chamber being open at the bottom and closed at the top and at the outer end, a fan compartment arranged at the rear end of the last named chamber in 85 communication with the said duct, and a fan mounted upon a separately actuated shaft for drawing air into and forcing it through the conditioning chamber as set forth. 90

9. In a drying machine, the combination with a drying chamber open at one end and closed at the other end and having a perforated ceiling and floor with a space respectively above and below them, of fan chambers arranged on each side of the drying chamber and to communicate with the said spaces in the drying chamber, each of said fan chambers being divided by curved transverse partitions into two portions, air circulating fans arranged in each fan chamber for causing the air to circulate through them in a vertical and downward direction, an exhaust fan at the closed end of the fan chamber for withdrawing moist air, means for separately actuating air circulating and exhaust fans, races arranged over each other and fixed to the longitudinal sides of the drying chamber at suitable distances apart, each race consisting of a number of strips of 100 angle iron of varying lengths to form two horizontal guides, a shaft or shafts arranged at the end of each of said guides and having sprocket wheels mounted thereon, an endless horizontal chain provided with projections and mounted upon said sprocket wheels near to each longitudinal side of the drying chamber, poles placed across the drying chamber with their ends in the said horizontal guides, a spur wheel mounted upon the end of the pole adapted to be intermittently meshed with racks arranged at 115 intervals apart on the said guides, means for actuating the said shafts, sprocket wheels and endless chains for causing the poles to 120 travel horizontally through the drying chamber, vertical guides arranged at one end of each pair of races, a second set of sprocket 125

wheels mounted upon the said shafts, endless chains provided with projections working over the second set of sprocket wheels for raising the poles from one race to that on a higher level, a conditioning chamber arranged at the open end of the machine, a separate fan chamber communicating at one end with an air duct and at the other with the conditioning chamber, means for oper-

ating the said fan for causing cold air to be drawn into the conditioning chamber and to pass through the material operated upon, and an inclined delivery chute at the open end of the machine as set forth.

ARTHUR NORRISON MARR.
